UNITED STATES PATENT OFFICE

138,318

DESIGN FOR A COMBINED BABY STROLLER AND FEEDER

Hiram Hopkins, Los Angeles, Calif.

Application June 8, 1943, Serial No. 110,405

Term of patent 7 years

(Cl. D14—14)

To all whom it may concern:

Be it known that I, Hiram Hopkins, a citizen of the United States, residing in the city of Los Angeles, county of Los Angeles, and State of California, have invented a new, original, and ornamental Design for a Combined Baby Stroller and Feeder, of which the following is a specification, reference being had to the accompanying drawing, forming a part thereof.

The single figure is a side perspective view of a combined baby stroller and feeder showing my new design.

I claim:

The ornamental design for a combined baby stroller and feeder, as shown.

HIRAM HOPKINS.
